United States Patent Office

Des. 195,553
Patented July 2, 1963

195,553

CHAIR

Richard A. Isola, Royal Oak, Mich., assignor, by mesne assignments, to Steelcase Inc., Grand Rapids, Mich.

Filed Aug. 3, 1962, Ser. No. 71,162

Term of patent 14 years

(Cl. D15—1)

FIG. 1.

FIG. 2.

FIG. 3.

FIG. 4.

FIG. 1 is a perspective view of the chair showing the design of my invention;

FIG. 2 is a front elevational view of the chair;

FIG. 3 is a rear elevational view of the chair illustrated in FIGS. 1 and 2; and

FIG. 4 is a side elevational view of the chair.

The dominant features of my design reside in those portions shown in full lines on the drawing.

I claim:

The ornamental design for a chair, substantially as shown and described.
